(57) **CLAIM**

The ornamental design for an axle hub conversion device, as shown and described.

DESCRIPTION

FIG. 1 is an exploded front view of an axle hub conversion device showing the claimed design;

FIG. 2 is an exploded rear elevation view thereof;

FIG. 3 is an exploded left side elevation view thereof;

FIG. 4 is an exploded right side elevation view thereof;

FIG. 5 is an exploded top plan view thereof;

FIG. 6 is an exploded bottom plan view thereof;

FIG. 7 is a top left perspective view thereof; and,

FIG. 8 is bottom left perspective view thereof.

The dashed broken lines in the figures show portions of the axle hub conversion device subject matter that form no part of the claimed design. The dot-dash broken lines in the figures indicate boundaries between claimed and unclaimed portions of the design. The shade lines in the figures show contour and not surface ornamentation. The dashed broken lines representing nuts illustrate environmental structure that forms no part of the claimed design.

1 Claim, 8 Drawing Sheets
